FIG. 1

FIG. 2

FIG. 5

FIG. 4

FIG. 3

FIG. 6

FIG. 1 is a left front view in perspective of a shelter showing my new design;

FIG. 2 is a left side view;

FIG. 3 is a front view;

FIG. 4 is a rear view;

FIG. 5 is a top view; and

FIG. 6 is a bottom view.

The right side view is identical with FIG. 2 except that the knob appears at the left rather than the right of the view, and the vent pipe is also reversed.

We claim:

The ornamental design for a shelter, substantially as shown and described.
